CASING HEAD AND BLOW-OUT
PREVENTERArthur J. Penick and Kirby T. Penick,
Houston, Tex.

Application June 26, 1933, Serial No. 677,656

5 Claims. (Cl. 286—16)

This invention relates to a combination casing head and blowout preventer.

An object of the invention is to provide apparatus of the character described particularly 5 adapted for use in carrying out drilling operations to prevent a blowout of gas under pressure in the well, where gas, under pressure, is present in sufficient quantities to cause a blowout and is also useful when it is desired to maintain the 10 drilling fluid, or other fluid, in the well, under pressure.

Another object is to provide a novel type of packing unit adapted to fit within the casing head to completely close the space between the 15 drill stem or other inner pipe and the casing head to prevent the escape of fluid from the well.

The invention also comprehends a packing unit which is adapted to be easily and quickly set in 20 position within the casing head about the inner pipe and secured therein without danger to the workmen.

The invention also includes novel means for 25 securing the packing unit in place in the casing head which may be readily released when it is desired to withdraw the packing unit and temporarily dispense with its use.

With the above and other objects in view, the 30 invention has particular relation to certain novel features of construction, operation, and arrangement of parts, an example of which is given in this specification and illustrated in the accompanying drawings, wherein:

Figure 1 shows a top plan view of the complete 35 apparatus.

Figure 2 shows a side view partly in section. 40 Figure 3 shows a side view partly in section, taken on the line 3—3 of Figure 1.

Figure 4 shows a plan view showing the packing 45 unit released, and

Figure 5 shows a side view partly in section of the resilient packing employed and the means for maintaining the same assembled with the 50 complete packing unit, and

Figure 6 shows a fragmentary sectional view 55 of a modified form thereof.

In the drawings the numeral 1 designates a well casing having the casing head 2 secured to the upper end thereof, and provided with an inside downwardly tapering seat 3. The casing

50 head has a lateral tapped hole 4 beneath said seat for the connection of a pipe thereto through which the fluid in the well may be led off or through which fluid under pressure may be forced into the well as desired. At its upper end the seat 3 is outwardly flared as at 5 and beneath

said flared portion the casing head has an annular external groove 6.

There is a packing unit, or assembly, formed of arcuate confronting segments indicated generally in Figure 1 by the numerals 7, 7. Each segment is composed of an arcuate metallic anchor 8 and an arcuate packing 9 secured to the underside of said anchor. The anchors 8 are hinged together at one side by means of a hinge plate 10 whose ends are fitted into slots 11 at 10 adjacent ends of said anchors and pinned therein by the pins 12.

At the opposite side of the packing unit there is a latch 13, hooklike in form, one end of which is pivoted in a slot 14 in one of said anchors and 15 whose hooked end is adapted to engage a pin 15 extending through the slot 16 of the adjacent end of the other anchor. Said hook is maintained in said engaging position by means of a flat spring 17 which operates against said latch. 20 The packing unit is so shaped that when latched around the drill stem or other inner pipe 18 it will completely surround said inner pipe and the outer surface of the packing 9 is tapered to conform to the shape of and to fit closely within 25 the seat 3.

Embedded within the packing 9 of each segment there is a rigid reinforcing member 18 preferably formed of metal and upstanding from this reinforcing member are the anchor rods 19, 19 30 which extend up through the anchor 8 above and whose upper ends are threaded to receive the nuts 20 whereby the packing may be maintained in place. In case the packing should become worn so as not to form a tight fit within the seat 35 3 the nuts 20 may be tightened up to draw up the reinforcing members 18 to thus effect the expansion of the corresponding packing 9 so that a tight fit will be secured between said packing and seat 3. The segments 7 have the handles 21 40 40 by means of which the packing unit may be handled.

The upper end of the anchors 8 of the packing unit is reduced forming an annular external shoulder 22 all the way around said unit and beneath said shoulder each anchor 8 has an annular tapering face 23 shaped to conform to the contour of and to fit closely into the flared upper end 5 of the seat 3.

The casing head 2 will usually be located beneath the derrick floor and when, for any reason, it may be desired to seat the packing unit in the casing head the segments of the packing unit may be swung open and then closed around the inner pipe 18 above the derrick floor and latched 55

and the inner pipe then lowered and the packing unit will be carried downwardly into the casing head and seated therein with the packing seated securely in the seat 3 and completely closing the space between the inner pipe 18 and the casing head and with the tapering face 23 seated on the flared portion 5 of the seat 3.

Novel means for securing the packing unit in place in a casing head and for releasing the same for withdrawal have been provided and which will now be described:—The securing means referred to comprises the arcuate clamps 24, 24 which are hinged together at one side by the hinge pin 25, said hinge pin passing also through the laterally extending ear 26 formed integrally with the casing head 2 whereby the clamps 24, 24 are supported on, and hingedly connected to, the casing head. The pin 25 is secured in place by a suitable cotter key 27.

At their other ends the clamps 24 have the outwardly turned grips or handles 28, 28 which are connected by means of a pull spring 29. This pull spring has its ends secured to the respective grips 28 by means of the clamp bolts 30. Between the grips 28 the clamp members 24 have the intermeshing lugs 31 having the pin bearings 32 which register when the clamps are secured around the packing unit and through which a pin 33 may be inserted to hold the clamps in securing position. This pin 33 may be secured against loss by means of a cable or other flexible tie member 34.

As more clearly shown in Figure 3 each clamp member 24 has an inside groove 35, providing the lower and upper inside arcuate shoulders 36, 37, the former of which is engageable underneath the external annular shoulder 38 on the casing head 2 and the latter of which is engageable over the external annular shoulder 22 of the corresponding anchor 8 whereby the packing unit will be secured in place in the casing head.

The clamps 24, 24 are flared upwardly as at 39 and when the packing unit is fastened around the pipe 18 and said pipe is lowered as hereinabove explained said packing unit will enter between the clamps 24, and the tapering faces 23 will contact with the correspondingly tapered portions 39 of said clamps and the packing unit will be guided into the casing head and the clamps 24 will be spread apart, the spring 29 yielding to permit this, and when the shoulders 22 of the packing unit clear the shoulders 37 of the clamps 24, said clamps will be drawn together by the spring 29 causing the shoulders 37 to engage over the shoulders 22 as shown in Figure 3 whereby the packing unit will be locked in place and the pin 33 may then be inserted through the bearings 32 to secure said clamps against spreading whereby the packing unit will be securely maintained in place against danger of displacement by the internal well pressure.

It should be noted that the shoulders 37 engage over the shoulders 22 of a packing unit, at diametrically opposite sides of said unit only, as more clearly shown in Figure 1, that is to say at opposing points approximately midway between the hinged ends of the clamp and the opposite ends thereof so that when it is desired to release the packing unit the pin 32 may be withdrawn and the grips 28 pulled apart until the shoulders 22 are cleared by the shoulders 37 and into the position more clearly illustrated in Figure 4.

If desired the lower end of the packings of said packing unit may be equipped with arcuate guides 40 which may be suitably secured to said

packing as shown in Figure 6 and whose outer sides have the inwardly tapering faces 41 whereby the packing unit may be guided into the casing without injury to the packing.

The drawings and description disclose what is now considered to be a preferred form of the invention, by way of illustration only, while the broad principle of the invention will be defined by the appended claims.

What we claim is:—

1. The combination with a casing head shaped to receive an inner pipe and having an inside seat, of arcuate confronting clamps hinged at one end to the casing head, yieldable means connecting the other ends of said clamps, a packing unit shaped to surround said inner pipe and adapted to be lowered with the pipe to seat in the casing head and close the space between the casing head and inner pipe, co-acting means on the packing unit and clamps effective to spread said clamps, upon lowering of the unit to permit said unit to seat on said seat, interengaging means on the casing head, packing unit and clamps arranged to be interengaged when the clamps are closed about the casing head and packing unit to secure the packing unit in the casing head.

2. A casing head shaped to receive an inner pipe, clamp means hinged on, and shaped to surround, the casing head, all in combination with a packing unit in the casing head shaped to surround the pipe and to be lowered with the pipe into position to close the space between the pipe and head, means normally holding the clamp means closely around the casing head, co-acting means on said unit and clamp means effective to actuate the clamp means into position to permit the packing unit to move into said closing position upon such lowering thereof, means on the packing unit and clamp means which normally interengage to secure said unit in the head, said holding means being yieldable to permit the clamp means to open to effect the release of the interengaging means whereby the unit may be removed from the head.

3. A casing head shaped to receive an inner pipe, clamp means hinged on, and shaped to surround, the head and having an upwardly flared portion, all in combination with a packing unit adapted to be secured around said pipe and to be lowered into the casing head to close the space between said pipe and head, yieldable means normally holding the clamp means closely around the casing head, said packing unit having an external, downwardly tapering face arranged to engage said flared portion to spread the clamp means to permit the unit to seat in the head, means on the packing unit and clamp means arranged to be interengaged, by said yieldable means, upon the seating of the unit in the casing head.

4. In a casing head shaped to receive an inner pipe, a packing unit composed of a plurality of segments, means to secure said segments about said pipe, clamp means hinged on, and adapted to surround, the casing head and interengaging means carried by said clamp means and packing unit respectively shaped to permit the packing unit to be lowered into the casing head and adapted to interengage to secure the packing unit in the casing head, co-acting means on the packing unit and clamp means effective to spread the latter upon passage of the former downwardly therethrough and means adapted to maintain said interengaging means in interengaging relation.

tion and being yieldable to permit the release thereof whereby the packing unit may be released from the head.

5. A casing head shaped to receive an inner pipe, confronting clamps hinged at one end on, and shaped to surround, said casing head and having grips at their other ends, yieldable means connecting said last mentioned ends of said clamps, a packing unit shaped to surround said

inner pipe and to fit within the casing head and close the space between the pipe and head, said unit having an external shoulder, and inwardly extending projections arranged approximately centrally between the ends of the clamps and engageable with said shoulder to secure the said unit in said head.
